UNITED STATES PATENT OFFICE.

FRANK F. FORSHEE, OF FLINT, MICHIGAN, ASSIGNOR TO WESTINGHOUSE ELECTRIC
PRODUCTS COMPANY, A CORPORATION OF MICHIGAN.

ELECTRIC RANGE.

1,374,558.

Specification of Letters Patent. Patented Apr. 12, 1921.

Application filed September 25, 1919. Serial No. 326,305.

To all whom it may concern:

Be it known that I, FRANK F. FORSHEE, a citizen of the United States, and a resident of Flint, in the county of Genesee and State of Michigan, have invented a new and useful Improvement in Electric Ranges, of which the following is a specification.

My invention relates to electrically-heated apparatus and particularly to electric ranges and ovens.

One object of my invention is to so arrange the wiring of a thermostat mounted in an oven door that there shall be no exposed conductors or conduit.

Another object of my invention is to so provide a terminal structure for the oven door of an electrical range having a thermostat mounted therein that connection may be made with the electrical-circuit conductors by placing the door in its operative position.

Another object of my invention is to provide a unit type of oven door for an electrical range which may be assembled with reference to the other parts of the oven or range with which it is to be associated.

Heretofore, a thermostat, mounted in the door of an electrical oven, has been connected to the electric circuit by means of conductors placed in a flexible armored conduit, the conduit emerging from the oven structure practically parallel to its front surface and entering the door at its hinged side. The conduit is therefore, subjected to a slight lateral twist every time the door is opened or closed. It was also necessary to mount the door in place very early in the process of assembly of the oven, as it was necessary to have the conduit in place in the oven before the heat-insulating material

was packed around the oven chamber proper. There was, therefore, always the risk of injury to the thermostat mounted on the door or even to the door itself, with a resulting necessity of disassembling the various parts, and the repair or replacement of the damaged parts.

In practising my invention, I provide the usual electric-oven door with hollow hinge pins and mount therein insulated contact terminals that project slightly beyond the outer ends of the hinge pins. Ordinary insulated conductors, placed between the double walls of the door, connect these contact terminals with a thermostat mounted in the door. Stationary contact members are so

mounted in the oven structure as to coöperate with the contact terminals mounted in the hinge pins to complete an electric circuit controlled by the operation of a thermostat. Hinge cover plates, which act also as hinge sockets, coöperate with the hinges to hold the door in operative position and also to cover the coöperating contact members, thus giving a neat and finished appearance to the oven structure.

In the single sheet of drawings, Figure 1 is a front view of an electric range in which is incorporated the device embodying my invention. Fig. 2 is a front view of a part of the oven, with a part of the cover member cut away, showing an assembled device embodying my invention. Fig. 3 is a side view of the cover member. Fig. 4 is a sectional view of the insulated stationary contact terminal, and Fig. 5 is a side view thereof.

An electric range 1 is provided with an oven 2 having a door 3 which is arranged to swing outwardly and downwardly on hinges 4. The hinges 4 are of L-shape, welded to the corners of the door and have hollow extensions 5 which act as hinge pins. An insulated contact terminal 6, having a projecting head 7, is mounted in each hollow hinge pin 5, being insulated therefrom by means of a tube 8 and a washer 9 of suitable insulating material. One end of an insulated conductor 10 is inserted and soldered in an opening 11 in the contact terminal 6, the other end of the conductor 10 being connected to one contact terminal of a thermostat 12 mounted in the front of the door 3, the conductor 10 being placed between the front and back plates of the door. The door 3 is of the usual double-wall construction, the spaces between the front and the rear wall being filled with heat-insulating material. The two contact terminals of the thermostat 12 are thus connected to the insulated contact terminals 6 located in the hollow hinge pins 5 by means of effectively concealed and protected conductors.

A stationary contact strip 13 is mounted on, and suitably insulated from, a bent sheet-metal strip 14 which is, in turn, suitably secured, as by rivets, to a sheet-metal web 15 that is mounted in the body of the oven 2. The bent form of the metal strip 14 provides a certain amount of flexibility to the mounting and may be so adjusted as

to cause the contact strip 13 to be pressed against the contact head 7 and thus insure good contact between the strip 13 and the head 7. The contact strip 13 is provided, 5 at its lower end, with a small projecting lug 16 formed to receive one end of a conductor 17 which may be soldered in place. The other end of the conductor 17 is connected to the tripping coil 18 of a circuit breaker 19 which controls the supply of energy from 10 a circuit 20 to a suitable resistor 21 located in the oven 2 and serving to heat the same. The coil 18, the circuit breaker 19 and the supply circuit 20 are shown schematically 15 only, as they may be placed in any suitable location in the range 1, and suitable conductors 17 and 22 may be used to connect the stationary contact strips 13 to the supply circuit, as shown in Fig. 1.

20 A hinge cover member 23 of substantially L-shape serves as sockets for the hinge pins 5, being provided with a substantially semi-cylindrical notch 24 in a side wall 25 of a raised portion 26, which raised portion acts 25 as a housing or cover for the contact mechanism. A boss or lug 27 is also provided to act as a stop for the door 3 when the same is opened to its fullest extent. The members 23 are suitably secured to the body of the oven 2 by a plurality of screws 28.

It will be noted that, by the use of the device embodying my invention, it is possible to assemble the door complete with the conductors and the thermostat and to test the 35 same without reference to the rest of the range. The stationary contacts 13 may be mounted in the oven at the proper time in the course of assembly and properly connected to the conductors 17 and 22, and the 40 contact terminals 13 may be protected against injury by mounting the hinge cover member 23 in its proper position. If desired, the oven door 3 may not be mounted on the oven 2 at the factory but may be 45 shipped separately and may be placed in its operative position when the range is installed on the customer's premises. The construction of the device is such that the thermostat is connected to the supply circuit by placing the oven door in its operative 50 position. As the doors may be built to standard size, any door may be applied to any oven with the assurance that it will fit properly and that the electrical contacts and 55 circuits will operate properly. I thus provide a unitary door structure which may be manufactured, tested and shipped separately, which may be easily and quickly placed in operative position on the range, 60 which is interchangeable and which, in case of necessity of repair, may be easily and quickly replaced by a new door without the assistance of skilled labor, and the defective or inoperative door may be repaired at the 65 shop.

Various modifications may be made in the device without departing from the spirit and scope of my invention, and I desire, therefore, that only such limitations shall be placed thereon as are imposed by the prior art or are specifically set forth in the appended claims.

I claim as my invention:

1. In an electrically-heated apparatus, the combination with a chamber, a hinged door 78 for said chamber having hollow hinges, a thermostat mounted on said door, an electric circuit and stationary contact terminals mounted adjacent to said chamber, of means 80 mounted in said hollow hinges for connecting said thermostat to said contact terminals by placing the door in its operative position.

2. In an electrically-heated apparatus, the combination with a chamber, a door, hollow hinge pins on said door, a thermostat mounted on said door and conductors connected to said thermostat, of terminal members connected to said conductors, said terminal members being mounted within said hollow hinge pins, and insulated therefrom and operating contact terminals mounted adjacent to said door.

3. In an electrically-heated apparatus, the combination with a chamber, a door, hollow hinge pins on said door, a thermostat mounted on said door, and conductors connected to said thermostat, of insulated terminal members connected to said conductors and mounted within said hollow hinge pins and extending beyond the outer ends thereof, and insulated contact members mounted adjacent to said chamber and engaging the projecting ends of said terminal members.

4. In an electrically-heated apparatus, the combination with a chamber, a door, hollow hinge pins on said door, a thermostat mounted on said door, conductors connected to said thermostat, of insulated terminal members connected to said conductors and mounted within said hollow hinge pins and extending beyond the outer ends thereof, insulated contact members mounted adjacent to said chamber and engaging the projecting ends of said terminal members, and hinge-pin cover members mounted adjacent to said chamber, co-operating with and covering said hollow hinge pins, contact terminals and contact members.

5. In an electrically-heated apparatus, the combination with a chamber, a hinged door having hollow hinges on said chamber, a thermostat mounted on said door, an electric circuit, and stationary contact terminals mounted adjacent to said chamber, of terminal members connected to said thermostat and mounted in said hollow hinges and co-operating with said stationary contact terminals to complete an electric circuit and a combined hinge-plate and contact cover member mounted on said chamber.

6. The combination of a chamber, a door therefor, a device carried by the door having electrical contact members adapted to engage, under predetermined conditions, 5 hinge pins carried by the door, insulated conductors leading from the contact members through said hinge pins and terminating at the ends thereof, detachably mounted

sockets for said hinge pins, and stationary terminals adjacent said sockets and engaging the exposed ends of the said conductors. 10

In testimony whereof, I have hereunto subscribed my name this 11th day of Sept. 1919.

FRANK F. FORSHEE.
